UNITED STATES PATENT OFFICE.

CHRIS JOHNSON, OF PORTLAND, OREGON.

DESIGN FOR A TOMBSTONE.

60,685.

Specification for Design. Patented Mar. 21, 1922.

Application filed October 13, 1920. Serial No. 416,767. Term of patent 3½ years.

To all whom it may concern:

Be it known that I, CHRIS JOHNSON, a subject of the Russian Government, residing at Portland, in the county of Multnomah and State of Oregon, have invented a new, original, and ornamental Design for Tombstones, of which the following is a specification, reference being had to the accompanying drawing, forming part thereof.

The figure is a front elevation of a tombstone, showing my new design.

I claim:

The ornamental design for a tombstone, substantially as shown.

CHRIS JOHNSON.
